UNITED STATES PATENT OFFICE.

CHARLES A. SCHREIBER, OF CEDAR LAKE, INDIANA.

SPARK PLUG.

Application filed February 21, 1927. Serial No. 169,930.

My invention relates to improvements in spark plugs, and it consists in the combinations, constructions, and arrangements herein described and claimed.

5 An object of my invention is to provide a spark plug which has a novel means for cooling the sparking terminal.

10 A further object of my invention is to provide a device of the type described which rotates the sparking terminal, thus preventing the collection of carbon thereupon.

15 A further object of my invention is to provide a device of the type described which has novel means for automatically holding the sparking terminal, irrespective of its rotative movement.

20 Other objects and advantages will appear in the following specification, and the novel features of the invention will be particularly pointed out in the appended claims.

25 My invention is illustrated in the accompanying drawings, forming part of this application, in which:

Figure 1 is a front elevation of my device.

Figure 2 is a section along the line 2—2 of Figure 1, and

Figure 3 is a bottom plan view of my device.

30 In carrying out my invention, I provide a central insulating body portion or core 1 having a longitudinally extending opening 2 centrally disposed therein. The upper end of the core 1, see Figure 2, is provided with an arcuate-shaped recess 3 while the lower

35 end of the core is provided with a seat 4.

The core 1 is provided with an enlarged portion 5 which is in the form of an annular flange. The lower portion of the core 1 is reduced in size at 6, thus forming a shoul-

40 der 7. A metal shell 8 is disposed concentric with the core 1 and provided with a gasket 9 which is disposed between the enlarged portion 5 and the shell, see Figure 2. A gasket 10 is disposed upon the enlarged

45 portion 5. A ring-like nut 11 is provided with threads 12 which are adapted to engage with threads 13 within the shell 8. As the nut 11 is moved downwardly within the shell 8, the core 1 is rigidly held in place.

50 A sparking terminal 14 has a relatively large arcuate-shaped contact end 15 which tapers inwardly to a point where the terminal is integral with a valve 16. The shell 8 is provided with an outwardly extending annular sparking surface 15'. A rod 17 is integral with the valve 16 and is provided

with a helical groove 18. The rod 17 is disposed within the opening 2 and provided with a threaded end 19 which is adapted to receive a ball 20 having slots 21 cut therein. 60 The ball 20 is provided with a flattened portion 22 which is adapted to contact with a lock nut 23. A hand screw or nut 24 is disposed upon the threaded portion 19.

From the foregoing description of the 65 various parts of the device, the operation thereof may be readily understood. In use, the vacuum created in the cylinder, not shown, upon the intake stroke of the piston, not shown, will cause the atmospheric pressure to force the valve 16 downwardly as it passes through the helical groove 18 so that air will be admitted to the cylinder in close proximity to the sparking terminal, thus insuring complete combustion of any carbon 70 in that portion of the mixture. This tends to keep the sparking terminal 14 and the sparking surface 15' clean. An improvement in the present instance lies in the provision of the spiral groove which distributes 75 the air or atmosphere in a circuitous path upon the sparking terminal 14 and the sparking surface 15'. This movement of the atmosphere passing through the slots 21 and the groove 18 tends to rotate the rod 17 together with the sparking terminal 14. This movement of the sparking terminal 14 constantly changes the positions of the points of contact upon the contacting surface 15', thereby preventing the shell adjacent the 80 sparking surface 15' from becoming heated to an intense heat as would occur if the sparking terminal 14 was stationary.

In Figure 2, the valve 16, the rod 17, and the ball 20 are shown in solid lines in their 85 uppermost or closed positions, and in dotted lines in their lowermost or opened positions. This showing is somewhat exaggerated for the purpose of clearness. In reality, the device is approximately one-half the size of 90 that shown in the drawings, and the movement of the valve 16, the rod 17, and the ball 20 is but a fraction of an inch.

I claim:

1. A spark plug provided with a central 105 core having a longitudinally extending central opening therein, a metal shell disposed concentric with said core and provided with an annular sparking surface positioned beyond one end of said core, a nut for rigidly 110 securing said shell to said core, a sparking terminal having a relatively small arcuate-

- shaped contact end positioned substantially adjacent the sparking surface, a valve integral with said sparking terminal and disposed in engagement with a valve seat positioned adjacent the opening in said core, a rod integral with said valve and disposed in said opening, means carried by said valve for allowing air to pass through said opening whereby said sparking terminal will be 10 rotated in a circuitous path and said sparking terminal together with said sparking surface cooled, said means comprising a ball having slots cut therein and receivable in an arcuate-shaped groove in the end of 15 said core opposite said valve, said rod having a helical groove extending from said valve around said rod and in communication with said slots, and means for locking said ball to said rod in any desired position.
- 20 2. A spark plug provided with an insulating core having a longitudinally extending opening therethrough, a conductor disposed in said opening, a valve secured to one end of said conductor for closing said opening,
- 25 a sparking terminal integral with said valve, a metal shell disposed concentric with said core and provided with a sparking surface disposed substantially adjacent said sparking terminal, and a ball-shaped mem- 30 ber disposed concentric with said conductor and adjustably secured thereto, said ball-shaped member being provided with slots in communication with said opening for permitting air to pass through said opening when said valve is moved away therefrom. 35
3. A spark plug provided with an insulating core having a longitudinally extending opening therethrough, a conductor disposed in said opening, a valve secured to one end of said conductor for closing said opening, 40 a sparking terminal integral with said valve, a metal shell disposed concentric with said core and provided with a sparking surface disposed substantially adjacent said sparking terminal, and a ball-shaped mem- 45 ber disposed concentric with said conductor and adjustably secured thereto, said ball-shaped member being provided with slots in communication with said opening, said conductor having a helical groove starting at 50 said ball in communication with the slots therein extending around said conductor and terminating at a point in substantial alignment with said sparking terminal, whereby air may be directed from said slots through 55 said groove to said sparking terminal.

CHARLES A. SCHREIBER.
